BEVERAGE DISPENSING TANK, OR SIMILAR ARTICLE

Richard T. Cornelius, Minneapolis, Minn., assignor to The Cornelius Company, Anoka, Minn., a corporation of Minnesota

Filed Jan. 5, 1966, Ser. No. 470

Term of patent 14 years

(Cl. D2—3)

FIG.1

FIG.5

FIG. 1 is a front perspective view of a beverage dispensing tank, or similar article, showing my new design.

FIG. 2 is a side elevational view thereof in reduced scale.

FIG. 3 is a bottom plan view thereof.

FIG. 4 is a rear elevational view thereof.

FIG. 5 is a top plan view thereof.

The ornamental encircling bands are shaded to denote that they are of a contrasting finish.

The dominant features of my design reside in the portions shown in full lines.

I claim:

The ornamental design for a beverage dispensing tank, or similar article, substantially as shown and described.
